UNITED STATES PATENT OFFICE.

ABRAHAM L. WELCH, OF RUSH RUN, WEST VIRGINIA, ASSIGNOR OF ONE-HALF TO
A. B. McCLELLAND, OF RUSH RUN, WEST VIRGINIA.

SECURING DEVICE FOR MINERS' LAMPS.

Application filed July 10, 1926. Serial No. 121,719.

The invention relates to means for securing miners' lamps on the head-wear of miners and has for its object the provision of a hook member made of a single length of wire to be threaded through openings in an angular plate to be secured to the crown and visor of a miner's cap, and having a U-shaped hook to engage a clip on the lamp, and also integral resilient members at the sides of the hook to engage 10 the lamp and tension its engagement with the hook.

The invention will be described in detail hereinafter and will be found illustrated in the accompanying drawings in which

15 Figure 1 is a side view of a miner's cap showing a lamp securing means associated therewith, the lamp being shown in broken lines.

Figure 2, a front view of the member to 20 be attached to the cap with the improved hook and plate, and

25 Figure 3, a fragmental sectional view on a plane indicated by the line 3—3 of Figure 1.

In the drawings, similar reference characters will be used to designate corresponding parts throughout the several views.

The means for securing a miner's lamp 30 to a cap comprises a plate 1 having its ends bent as shown at 2 to be secured to the crown of a miner's cap A, and as shown at 3 is secured to the visor of the cap, any preferred means of securing the plate 1 to the cap being used. The hook member is 35 formed of a single length of wire that is bent intermediate of its ends to form an inverted U-shaped hook 4, having the bight of the hook compressed to form a narrowed 40 portion 5 to aid in attaching the lamp to the hook. The length of wire is bent upwardly as shown at 6 on each side of the U-shaped member 4, and is threaded through openings 7 and 8 arranged on each

side of the hook. The end of the wire 45 emerging from the opening 8 is then bent outwardly and downwardly from the plate as shown at 9, and then downwardly substantially parallel to the plate 1, as shown at 10, and its extremity bent inwardly and 50 upwardly as shown at 11.

The lamp B is provided with a clip 12 that is soldered or otherwise secured to the lamp and spaced therefrom to receive the U-shaped member 4, and when in position 55 the parts 10 by engaging the clamp, said parts setting out farther from the plate 1 than the hook 4, form resilient members to 60 yieldingly hold the lamp in engagement with the hook to prevent casual displacement thereof.

It will be apparent that the portions of the wire threaded through the openings 7 and 8 will securely hold the hook member 65 on the plate, but to prevent rattling and to insure against movement of the hook member on the plate, the portions 13 of the wire at the rear of the plate may be soldered as shown at 14 for the purpose stated.

What is claimed is:

A securing device for miners' lamps having attaching clips thereon, comprising a hook member formed of a single length of wire bent intermediate of its ends to form an upstanding U-shaped member to engage the clip on the miner's lamp, the wire at each side of the U-shaped member bent laterally and upwardly, the wire at the ends of said upwardly bent portions bent away from the upwardly bent portions and downwardly at each side of the U-shaped member and adapted to engage the lamp at each side of the U-shaped member to prevent casual displacement of the lamp from 75 said member.

In testimony whereof I affix my signature.

ABRAHAM L. WELCH.
